METAL SAWING MACHINE

Adam Ziska, Wauwatosa, Wis., assignor to Peerless Machine Company, Racine, Wis., a corporation of Wisconsin

Application August 6, 1943, Serial No. 497,568

23 Claims. (Cl. 29—73)

1

This invention relates to improvements in power-operated metal hack saw machines which while capable of embodiment, with singular advantages, in the duplex type of metal sawing machine, also incorporates in its construction various novel features susceptible of advantageous use in metal sawing machines where only a single saw is used.

One of the objects of the invention is to constitute and organize a machine of this character that is strong, rugged, and durable in construction, efficient and rapid in operation, and so controlled in its action that each sawing cycle is largely automatically governed although provision is made for manual control at all times.

Another object of the invention is to so constitute a machine of this character and having the advantages mentioned in that it provides a unitary, self-contained construction in which the fluid pressure motors that reciprocate the feed and saw frames are completely enclosed and yet are closely and compactly as well as effectively organized with the parts with which they are interconnected. The pumps which supply the fluid under pressure to the fluid pressure motors are also housed and carried by the feed frame, and the electric motor which drives both pumps is carried by the feed frame though disposed exteriorly thereof. The necessity of resorting to flexible or telescopic connections between the pumps and the fluid pressure motors is avoided.

Another object of the invention is to provide an improved feed and saw frame construction and organization operable to advantage for single sawing or for duplex sawing when two sets of saw and feed frames are operatively interrelated.

A further object of the invention is to provide novel and advantageous means for tensioning the saw and its backing plate and for controlling the interengagement between the saw and its backing plate.

Other objects and advantages reside in certain novel features of the construction, arrangement, and combination of parts, which will be herein-after more fully described and particularly pointed out in the appended claims, reference being had to the accompanying drawings forming a part of this specification, and in which:

Figure 1 is a view in side elevation illustrating a duplex metal hack saw machine embodying the present invention;

Figure 2 is a fragmentary view partly in side elevation but mainly in longitudinal, vertical cross section, illustrating the fluid pressure motor employed to reciprocate each feed frame and also

2

the motor and pump which provide the fluid pressure medium for actuating the motor;

Figure 3 is a view in end elevation of the metal hack saw machine illustrated in Figures 1 and 2;

Figure 4 is a fragmentary view in top plan of the metal hack saw machine illustrated in Figures 1 to 3;

Figure 5 is a view partly in top plan and partly in transverse, horizontal cross section, illustrating the structure of one of the feed frames and of its associated saw frame, a view being taken on line 5—5 of Figure 6;

Figure 6 is a fragmentary view, partly in side elevation and partly in longitudinal, vertical cross section, taken on line 6—6 of Figure 5;

Figure 7 is a view in vertical, transverse cross section taken on line 7—7 of Figure 8;

Figure 8 is a fragmentary view partly in top plan and partly in longitudinal, horizontal cross section, illustrating the slip clutches employed to protect the tensioning means for the saw blade and the backing plate and also the eccentric gear utilized to control the operative relationship between the backing plate and the saw blade;

Figure 9 is a detail view in side elevation showing the structure of the eccentric gear employed to control the operative relationship between the backing plate and the saw blade;

Figure 10 is a view in vertical cross section, taken on line 10—10 of Figure 8, with parts shown in elevation for the sake of illustration;

Figure 11 is a fragmentary view on an enlarged scale, and in side elevation, to better illustrate the manner in which the saw blade and the backing plate are combined with the saw frame and controlled as to position and tension;

Figure 12 is a fragmentary view partly in side elevation and partly in cross section and diagrammatically illustrating the valves which take part in the control of the sawing and return strokes of the saw frame and the feeding and withdrawal strokes of the feed frame, and also illustrating the cams and the trip fingers combined with the saw frame and valves and employed for the purpose of automatically operating the valves;

Figure 13 is a view taken on line 13—13 of Figure 12 and further illustrating the cams and trip fingers shown in Figure 12;

Figure 14 is a detail view in side elevation of one of the feed frames;

Figure 15 is a view in vertical cross section taken on lines 15—15 of Figure 14;

Figure 16 is a detail view in top plan of one 55 of the saw frames;

Figure 17 is a detail view in side elevation of one of the saw frames;

Figure 18 is a detail view in diametrical cross section showing the valve mechanism employed to regulate the extent of withdrawal of the saw blades on each return stroke and also the relief valve mechanism;

Figure 19 is a diagram of the electrical circuit that may be employed to take its part in the control of the operating cycles of the machine;

Figure 20 is a diagram of the hydraulic circuits employed to control various phases of the operating cycles of the machine; and

Figure 21 is a detail view in top plan of one of the tracks or ways provided on the base for cooperation with a feed frame.

Referring to the drawings, and more particularly to Figures 1, 3, and 4, it will be seen that the duplex metal hack saw machine embodying the present invention generally comprises a base A which may be a metal casting supported on a suitable foundation. Fitted to guiding ways in the base A, for sliding horizontal movement with respect thereto, are a pair of similar feed frames, designated generally at F₁ and F₂. These feed frames F₁, F₂ are of identical construction, but are oppositely disposed. Combined with each feed frame is a vertically reciprocal saw frame S. Mounted on each saw frame S, and tensioned and positioned in a manner to be hereinafter more fully described, is a saw blade B and backing plate P. Supported on the base on the opposite sides of the feed frames are the work tables, W₁ designating the front work table equipped with suitable gauges G, and W₂ designating the rear work table, which is slotted and equipped with suitable fixtures to maintain the work in position for sawing. The confronting edges of the work tables are suitably spaced to provide clearance for the saw blade B and backing plate P.

The base A is of hollow construction, and its main longitudinal portion, on which the feed frames F₁ and F₂ are mounted, is provided with parallel, undercut, longitudinal ways, designated at 1. These ways, which are of bar- or rail-like form, are of similar construction and are shown in end elevation in Figure 3 and in detail in Figure 21. They are securely fixed to the horizontal top portion of the base by means of countersunk screws, bolts, or other fastening devices, and they are designed and proportioned to slidably interfit with similarly formed guide grooves 3 machined on the undersides or bottoms of the feed frames F₁ and F₂ (see Figures 3 and 15). Suitable gibs 4 are combined with this interconnecting and guiding structure to take up wear and provide for adjustment.

As indicated, the feed frames F₁ and F₂ are of identical construction although oppositely arranged. They are shown in detail in Figures 14 and 15. Each feed frame is generally of rectangular construction and includes a hollow horizontal base section 5 and hollow and vertically disposed uprights or standards 6, which have their lower ends integral with the outer ends of the base section 5 and are disposed parallel to each other. The upper ends of the uprights or standards 6 are cross-connected by an upper cross member 7 which is also of hollow, box-like construction.

The base section 5 of each feed frame is dimensioned and proportioned and otherwise designed to support and house the fluid pressure motor which drives the frame, and to support and

suitably house the motor-driven pump which supplies the fluid under pressure to said motor.

As illustrated in Figures 2, 14, 15, and 21 the central portion of the bottom wall of the base 5 is provided with a raised portion 8 formed with downwardly opening recess which overlies an elongated longitudinal slot 9 provided in each undercut guide rail 1 and a similar and registering elongated slot 10 provided in the top wall of the base A under each slot 9.

The fluid pressure motor, which drives each feed frame, has its cylinder 11 disposed in the recess 8 and slots 9 and 10. Each cylinder 11 is securely fixed to the wall of the raised portion 8, and consequently is fixed to and moves with its feed frame. A piston 12 is slidably fitted in each cylinder and has a piston rod 13 projecting through a stuffing box 14 provided at one end of each cylinder 11. The outer end of each piston rod 13 is anchored to its associated guide rail 1, and consequently to the base A. For this purpose, each guide rail 1 is provided with a vertical hole 15 therethrough and disposed adjacent to though spaced from one end of the slot 9 thereof. The portion 2 of each guide rail 1, located between its hole 15 and the adjacent end of its slot 9, is formed with a lengthwise hole 2' whose axis is coincident with the longitudinal axis of the guide rail 1. The outer end of each piston rod 13 is reduced and shouldered and interfits with the hole 2' of portion 2 of its rail 1. A nut 15', threaded on the extreme outer end of each piston rod 13, coacts with the portion 2 to fix each piston rod to its guide rail 1.

The fluid pressure medium, which is alternately supplied to the opposite ends of the cylinder 9, is derived from a pump 16, which may be of any suitable type and which is mounted on a supporting bracket 16' fixed to one end of the base 5 of the feed frame. To the same end wall of the base 5 of each feed frame is secured an electric motor 17, which, however, is disposed on the opposite side of such end wall from the bracket 16 and is located outside of the confines of the feed frame although entirely supported thereon and moving therewith.

The armature shaft 18 of the motor 17 is suitably coupled to the rotor of the pump 15 and serves to drive the rotor of the pump and incidentally to build up suitable pressure that is required to actuate the piston 12 of the fluid pressure motor which serves its feed frame. The construction described is advantageous in that the means which is employed to reciprocate the feed frame is of the self-contained type and is directly connected thereto and carried thereby. Any necessity of resorting to flexible or telescopic connections is avoided.

Each saw frame S is of square construction, as illustrated to advantage in Figures 1, 6, and 17. Each such saw frame is made up of upper and lower cross members, designated at 25 and 26, interconnected at their ends with vertical side members 27 and 28, these parts being combined into one unitary structure by welding or by other appropriate means of securing them together. Welding, however, is preferred.

The side members 27 and 28 of the saw frame have their outer portions of V shape in horizontal cross-section to provide slides 29 and 30 which slidably interfit with correspondingly formed guide grooves 31 and 32 (see Fig. 5) formed in guide rails 33 and 34, bolted or otherwise suitably fixed to the confronting or inner walls of the vertically disposed uprights or standards 5 of the

feed frame (see especially Figures 5, 6, 16, and 17). The center line of the slide 29 is offset from the center line of the slide 30 on each saw frame to permit the two saws to operate in the same sawing plane while minimizing the moment arm between the application of the sawing force to the saw and its absorption by the saw frame. This is accomplished as shown in Figures 5 and 16 by making the upper cross member 26 of each saw frame of the offset construction illustrated 10 and correspondingly forming each lower cross member 25.

Each saw blade B is anchored at its lower end to the lower cross member 25 of its saw frame by means of a lower saw grip 35 which comprises 15 a short rectangular bar provided with a transverse slot 36 in which the lower end of the saw blade is fitted and to which it is secured by dowel pin 38 (see Figures 7 and 11) and in which it is clamped by virtue of the action of a clamp screw 37. Each lower saw grip or anchor 35 is fitted in a groove provided therefor in the lower cross member 25 of its saw frame and is securely held in position by dowel pin 40 and stud bolt 41. The upper end of each saw blade is also interfitted with the slot 42 provided in the lower end of an adjustable upper saw grip 43 and is fastened to this upper saw grip by dowel pin 44 and clamp screw 45 as before. The upper saw grip is bar-like in construction but elongated, and a portion of its rear face is provided with rack teeth or worm teeth 46. The upper saw grip has tapering side edges to adapt it to slide in an undercut guide groove 47 provided in the upper cross member 26 of the saw frame. The top of the upper cross member of the saw frame, just in back of the guide 47, is formed with a bearing socket 49 to receive a driving worm 50. The worm 50 meshes with the teeth 46 of the adjustable upper saw grip. It has projecting from its lower side, and coaxially disposed with it, a mounting shaft 51 which is rotatably fitted in a bearing opening 52 provided therefor in the upper cross member 26 of the saw frame. A screw 53, threaded through the upper cross member of the saw frame, projects into an annular groove 54 of the shaft 51 to prevent it from moving axially although leaving it free to rotate. Obviously, when the worm is turned in one direction, the upper saw grip will be moved upwardly and tensioning applied to the saw blade, whereas when it is moved in the opposite direction the upper saw grip will move downwardly and will reduce or relieve the tension. To facilitate turning of the worm 50, and also prevent overstressing of the parts, its squared tool-engaging stud 55 is not rigidly connected to it but rather is connected to it through a slip clutch designated generally at 56. This slip clutch comprises a hub 57 formed integral with the tool-engaging stud 55 and fitted for rotation in a correspondingly formed cavity provided therefor in the center of the worm. Spring-projected balls 58, carried by the hub and normally interlocked with semi-spherical cavities 59, are provided in the socket in the worm. When, however, an excessive force is placed on the parts, the springs yield, the balls slip out of the recesses, and the stud 55 turns without any appreciable torque being transmitted to the worm.

Each backing plate P is also anchored to the lower member 25 of its saw frame with respect of any vertical movement although it may be shifted horizontally. For this purpose (see Figs. 10 and 11) a lower plate anchor in the form of a rectangular bar 60 is fitted in a groove at the lower

cross member of its saw frame and is securely fastened in position in this groove by countersunk stud bolts 61. Each lower plate anchor has integrally formed therewith an outwardly projecting and downwardly acting hook or grab 62, the bill or active portion of which is undercut. The ends of the backing plate P are of thickened construction as they are reinforced by reinforcing plates welded thereto and in effect integral therewith. The design is such that the ends of the backing plate are of the same thickness as the saw grips. A slot 64 is formed in the lower end of the backing plate and has its lower wall 63 angled or slanted to effectively engage and cooperate with the undercut surface of the bill of the hook 62, which in the assembly is received in the slot 64. The slot 64 and hook or bill 62 are so dimensioned and proportioned that while the backing plate may not move vertically with respect to the hook or bill, it may slide horizontally with respect thereto.

An adjustable upper plate anchor 65 is provided and is slidably interfitted within a vertical, undercut guide slot 65' provided therefor in the upper cross member of the saw frame. This upper plate anchor is provided with an upwardly facing bill or hook 66 which coacts with the slot 67 provided in the upper end portion of the backing plate and is effective to control the tension of the backing plate while leaving it free to shift horizontally. For moving the upper plate anchor up and down, and thus controlling the tension of the backing plate, a worm 69 is combined with the upper cross bar of the saw frame in the same manner as the worm 50 and interengages with worm teeth 70 on the back of the adjustable upper plate anchor. The worm 69 may be actuated from a tool-engaging stud 71 operatively interrelated with the worm through a slip clutch 72 as before. A cover plate 73 retains the slip clutches in the cavities of their worms.

In addition to this mechanism for controlling the tension of the backing plate, means is provided to shift it horizontally—that is, toward and away from the saw blade. This means includes upper and lower clips 75 riveted or otherwise suitably secured to the backing plate and having their inturned ends 77 embracing adjusting blocks 78. These blocks 78 are mounted on eccentric pins 79 fixed to shafts 80 rotatably mounted in the cross members of the saw frame and controlled as to adjustments by means of adjusting plates 81 which have a segmental slot 82 therein adapted to coact with clamping nut and bolts 83 whereby the adjusting plate may be held in any adjustment.

Each saw frame is reciprocated vertically by means of a pair of fluid pressure motors, designated at 85 and 86, disposed on the opposite sides of the saw frame. The motors 85 and 86 are of identical construction and are enclosed in the hollow uprights or standards 6 of the feed frames. The cylinder 87 of each motor is fixed to its feed frame and this may be accomplished by means of the same bolts designated at 87', which fix the guide rails 33 to the feed frames (see Figure 6). A piston 88 is fitted in each cylinder 87 and has a piston rod 89 fixed thereto and projecting exteriorly through a suitable packing gland at the lower end of the cylinder. The lower end of each piston rod is fixed to a driving arm 90 which is interfitted with notches 90' formed in the slides of the saw frame and secured in interfitted relation therewith by means of stud bolts 91. The driving arms operate through ver-

tical slots provided therefor in the uprights or standards 6 of the feed frames and in the guide rails 33. Obviously as the pistons 88 reciprocate in their cylinder 87, the driving arms moving vertically in the slots will reciprocate the saw frames.

The saw frames S have a substantial vertical stroke, in the particular machine shown a vertical stroke of six inches. The machine as viewed in Figure 1 would appear not to provide the clearance necessary for such a stroke but that such clearance is available may readily be realized upon inspection of Figure 15 which illustrates that the feed frames are pocketed as at 6' to allow the saw frame to descend as required. Also the upper cross member 7 of each feed frame is formed with a vertical opening 92 to provide for convenient access to the tool-engaging studs 55 and 71.

The hydraulic circuit which regulates the action of the fluid pressure motor which drives each feed frame, hereinafter called feed motor, and the fluid pressure motors which drive each saw frame, hereinafter called saw motor, is illustrated diagrammatically in Figure 20. There is one such circuit for each feed and saw frame assembly. In each of these hydraulic circuits the pump 16 has its discharge port connected by conduit 93 to the intake port 94 of a control valve designated generally at 95.

The control valves 95 function, in one of their positions, and in conjunction with the other instrumentalities of the hydraulic circuits, to cause continuous and automatic repetition of the operations which comprise the sawing cycles; namely, downward movement of both saw frames S and both saws B on each sawing stroke, simultaneous feeding movement of both feed frames F1, F2, and of both saws B into the work on each sawing stroke, upward or return movement of both saw frames S and both saws B at the completion of each sawing stroke, and limited retraction or withdrawal of both feed frames F1, F2, and both saws B simultaneously with their upward or return movement.

In the other position of the valves 95 they function to cause complete return of the feed frames F1, F2, and saws B to starting position.

Each control valve 95 is interconnected in a special way with valve means 96. The valve means 96 is in reality two valves, combined into one, for the sake of convenience and simplicity of structure. The lower portion 97 thereof functions as a distributing or reversing valve for the feed motor with which it is associated while the upper portion 98 thereof is a pilot valve to regulate the action of a reversing or distributing valve 99 employed for the purpose of controlling the operation of its pair of saw motors 85 and 86.

Of course the distributing or reversing valve 97 and the pilot valve 98 could be separate valve structures.

The control valve 95 is preferably electromagnetically controlled and for this purpose it may have a solenoid 100 combined with its valve plunger or piston 101. When the solenoid is energized it raises the valve piston 101 and so positions the valve as to provide for the automatic repetition of the operations which comprise the sawing cycles. When the solenoid is deenergized the valve piston 101, under the influence of suitable biasing means, such as a coil spring 102, is shifted to its other position wherein it effects complete return, as will be hereinafter more fully described.

The distributing or reversing valve 97 and the pilot valve 98 are synchronized in their action with the vertical movements of their saw frame S. In the construction shown in Figure 20 these valves 97 and 98 are illustrated as having a common plunger or valve piston 103 connected by a lost motion connection to one of the piston rods of one of the saw motors as illustrated diagrammatically in Figure 20. Such lost motion connection includes an arm 89' fixed on the piston rod 89 of one of the saw frame actuating motors 87 and formed with a hole through the extended end thereof. The stem 103' of the valve piston 103 extends through the hole in the arm 89' and is freely slideable therein within the limits imposed by collars 104 and 104' fixed on such valve stem.

Figures 12 and 13 diagrammatically illustrate that rotary valve means designated at 96a and 99a may be employed in lieu of the valve means 96 and 98, respectively, of Figure 20. When rotary valve means are employed, cams 96b and 96c may be mounted on one of the driving arms 90 in cooperative relation to cam or wiping fingers 98d and 98e connected to the rotary members of said valves 96a and 99a.

The control valve 95, distributing or reversing valve 97, pilot valve 98, and distributing or reversing valve 99 are shown as being piston valves. This, of course, is for the sake of illustration. Obviously, rotary valves or other suitable types of valves might be employed.

However, in the construction shown, the control valve 95 has a valve casing or valve body 105 preferably of cylindrical form. Opposite or angularly spaced from its intake port 94 are two outlet ports 106 and 107, these ports being located symmetrically with respect to the intake port 94 in a direction lengthwise of the valve body. Axially spaced from the ports 106 and 107 and on the same side of the valve are return ports 108 and 109. On the opposite side of the valve from the outlet and return ports and axially spaced from the intake port 94 are discharge ports 110 and 111. The piston or plunger 101 of the control valve 95 is provided with a piston head 112 which in the position shown in Figure 20 blocks communication between the intake port 94 and the outlet port 107, but establishes communication between this intake port 94 and the outlet port 106. Any communication between the intake port 94 and the return ports 108 and 109 is blocked by piston heads 113 and 114 suitably machined on the piston of the valve.

Communication between the return ports 108 and 109 and the discharge ports 110 and 111 is under the control of piston heads 113 and 114 provided on the piston of the valve.

The distributing or reversing valve 97 and the pilot valve 98 have, in the construction illustrated, a common valve body 117 which also may be of cylindrical form. The distributing or reversing valve section 97 of this common valve body is provided on one side with ports 118, 119 and 120, and on its opposite side with ports 121 and 122. Not only does this valve means 96 which is comprehensive of the two valves named have a common valve body, but it also has the common valve piston or plunger 103. The lower section of this piston or plunger 103 which functions as an element of the distributing or reversing valve is provided with piston heads designated at 123, 124 and 125. The upper or pilot section 98 of the valve body 117 is provided on one side with ports 126, 127 and 128, and on its opposite sides

with ports 129 and 130. The upper section of the piston or plunger serving the pilot valve 98 is provided with piston heads 131, 132 and 133. Intermediate the distributing or reversing section 97 of the valve means 96 and its pilot section 98 with the common plunger 103 of the valve is provided with a blocking and guiding piston head 134 which is a working fit in the intermediate portion of the valve body.

The feed port 106 of the control valve is connected by a pipe or conduit 135 to the port 119 of the distributing or reversing valve 97. This port 119 of the distributing or reversing valve 97 alternately communicates with the ports 121 and 122, communication between the port 119 and the port 121 occurring when the saw frame is at the top of its stroke. As the saw frame descends, this communication between ports 119 and 121 is blocked and as the saw frame reaches the lower end of its stroke the piston head 124 moves downwardly to provide for communication between the port 119 and the port 122. The port 121 connects by means of a pipe or conduit 136 with a feed pressure control 137 of standard construction, and also with the gauge 138. A branch conduit 139 in open communication with the conduit 136 connects to a stroke limiting device 140, the latter in turn connecting through a pipe or conduit 141 with one end of the feed cylinder 11. The stroke limiting device 140 is identical with that described and claimed in United States Letters Patent No. 2,202,256, granted May 28, 1940, to O. M. Jensen et al. for Hydraulic feed for power driven hack saws, and comprises in general a cylinder 140a and a piston 140b (see Figure 18), the piston 140b being of limited stroke and having a check valve 140c therein which permits the free flow of the fluid pressure through the piston 140b in one direction, but blocks all flow through the piston 140b in the opposite direction. However, when the pressure is exerted against the check valve 140c, the piston may move a limited distance and consequently permit a limited displacement of the fluid under pressure. The function of this device is to allow the full force of the hydraulic pressure to feed the saws into the work, but to limit the extent of their withdrawal or retraction on each return stroke.

With the valves in the position described, the fluid under pressure is supplied to the left-hand end of the feed cylinder 11, as viewed in Figure 20, and the cylinder 11 is driven with respect to its piston 12 to feed its saw into the work. At the same time fluid is exhausted from the opposite end of the cylinder, since it flows through conduit or pipe line 142 to port 122 of valve 97, thence across the valve to port 120, through pipe lines 143 and 144, to the return port 109, through the valve 95, to the discharge port 111, and then through pipe lines 145 and 146, back to the sump or oil reservoir.

At the completion of the sawing stroke, the valve plunger 103 has moved downwardly from the position shown in Figure 20 to the lower limit of its stroke, so that the circulation or distribution of the fluid under pressure is reversed, for at such time the fluid pressure flows from the port 106 of the control valve through the pipe line or conduit 135, port 119, as before, but now the port 121 is blocked, whereas the port 122 is in communication with the port 119. Consequently the fluid pressure flows from the port 122 through a conduit 147 which connects with the conduit 142. Thereupon the cylinder 11 is displaced to the right as viewed in Figure

20, but for a limited distance only, since it can only move as far as the piston 140b of the stroke limiting device 140 will allow it. There is, however, a limited movement sufficient for adequate withdrawal or retraction of the saw from its work during its return stroke. The fluid under pressure displaced by the stroke limiting device 140 moves back through conduits 139 and 136, to port 121, then across to port 118, and from port 118 through conduits 148 and 144, to return port 109, then across to discharge port 111 and back through the pipes 145 and 146 to the sump.

During the time that the feed cylinder 11 is feeding its feed frame and consequently the saw into the work, the saw frame is being driven downwardly through its sawing stroke by means of the fluid pressure motors 85 and 86. On the other hand, when the feed cylinder is actuated to withdraw or retract the feed frames and consequently the saws from the work, the saw frames are being moved upwardly by the motors 85 and 86 on their return stroke. The motors 85 and 86 are served by a separate pump designated at 150 supported with the pump 16 on the bracket 16' and like the pump 16 driven by the electric motor 17. The discharge port of the pump connects to a flow control and relief valve 151 of conventional construction, which in turn has a pipe line 152 leading therefrom. A gauge 153 may be tapped into pipe line 152. A conduit 153' leads from the pipe line 152 to the intake port 154 of the four-way valve 99 which controls the distribution of the fluid pressure to the motors 85 and 86. This valve 99 is of conventional construction and is shown diagrammatically as having a cylindrical valve body 155. On the same side of the valve body as the intake port 154 are exhaust ports 156 and 157 which lead back to the oil sump or reservoir. On the opposite side of the valve body from the ports 154, 156 and 157 are outlet ports 158 and 159. Conduit 160 leads from the outlet port 158 and has branches 161 and 162 leading to the lower ends of the cylinders 87 of the fluid pressure motors 85 and 86. Similarly, a conduit 163 leads from the outlet port 159 and has branches 164 and 165 communicating with the upper ends of the cylinders 87 of the motors 85 and 86. The valve proper is in the form of a piston 166 shiftable lengthwise in the valve body and having three piston heads serving in one position of the piston to supply fluid under pressure to the upper ends of the cylinders 87 of the motors 85 and 86, while at the same time exhausting fluid under pressure from the lower ends of such cylinders. In the other position of the piston 166 the action is reversed and fluid under pressure is supplied to the lower ends of the cylinders 87 of the motors 85 and 86 while it is exhausted from the upper ends thereof. This piston valve 166 is automatically shifted, and shifted in synchronism with the other operations by the pilot valve 98. For this purpose one end of the valve body 155 is connected by pipe line 167 to the port 129 of the pilot valve, whereas the opposite end of the body is connected by pipe line 168 to the port 130 of the pilot valve. The intake port 127 of the pilot valve is connected to the conduit 152 and consequently receives the pump pressure. The ports 126 and 128 of the pilot valve are connected by pipe lines 169 and 170 to the oil reservoir or sump.

With this construction when the piston of the pilot valve 98 is in the position shown in Figure 20, fluid under pressure flows through the pipe

11

line 152 to port 127, then across the valve to port 129, thence up through the pipe line 167 to the right-hand end of the valve body 155. The pressure supplied to the right-hand end of the valve body 155 shifts this piston 166 to the left, thereby causing the fluid under pressure flowing to the intake port 154 to be supplied to the outlet port 159 and through the pipe line 163 and its branches 164 and 165 to the upper end of the cylinders 87 of the motors 85 and 86. The sawing stroke ensues. At the same time the fluid under pressure is exhausted from the lower ends of the cylinders 87 of the motors 85 and 86 through the pipe line 160 and its branches 161 and 162, to port 158, and across the valve 15 to the exhaust port 156.

Upon the completion of the sawing stroke the pilot valve is shifted downwardly so as to block communication between the intake port 127 and outlet port 129, while establishing communication between the inlet port 127 and the outlet port 130. When this occurs fluid under pressure flows from the outlet port 130 through the pipe or conduit 168 to the left-hand end of the valve body 155. Valve piston 166 is then shifted to the right with the result that fluid under pressure is supplied to the lower ends of the cylinders 87 of the motors 85 and 86 and exhausted from the upper ends of these cylinders.

When the solenoid 100 is deenergized and the piston of valve 95 drops to its lower position, the valve means 96 is bypassed and a hydraulic circuit is established to the feed motor through the control valve 95 to cause the feed motor to effect complete return of the feed frame, that is a full return to starting position. At such time fluid under pressure flows from intake port 94 of valve 95 across to outlet port 107 and then through a pipe line 171 to pipe line 142 and into the right-hand end of cylinder 11 as viewed in Figure 20. Fluid pressure is exhausted from the opposite end of cylinder 11 through pipe 141 to pipe 172. Pipe 172 leads to port 108 which in lower position of control valve 95 is in communication with discharge port 110. Port 110 communicates through pipe 173 with pipe 146 leading back to stump.

The electric circuit for the motor 17 which drives the pumps combined with each feed frame is shown in diagram in Figure 19. There is nothing special about the circuit itself. Any standard circuit may be employed. It is desirable to incorporate in the circuit a starting switch 176, a stopping switch 177 and a reversing switch 178. In addition, a left-hand and a right-hand micro-switch designated at 179 and 180, respectively, are incorporated in the circuit. These switches 179 and 180 are preferably incorporated in a single housing 181 (see Fig. 1) fixed to the lower portion of the feed frame and their operating plungers coact with adjustable trip cams 182 and 183. The cams 182 and 183 are adjustable along a slotted guide 184 carried by the base of the machine. The guide 184 may be provided with a scale 185 to facilitate precision adjustment of the trip cams. The trip cams 182 and 183 may be adjusted to cause the sawing to start at any selected starting point and proceed to any other selected stopping point within the range of action of the machine, and when the sawing has progressed to the stopping point the trip cam 182 acting on micro-switch 178 reverses the action and causes the feed frame to return automatically to its starting position.

While the invention is capable of advantageous embodiment in a duplex type of sawing machine,

12

obviously many of its features may be employed to advantage where only a single saw is used. In such a case there would, of course, be only one feed frame and one saw frame.

5 While I have shown and described one construction in which the invention may be advantageously embodied, it is to be understood that the construction shown has been selected merely for the purpose of illustration or example, and 10 that various changes in the size, shape, and arrangement of the parts may be made without departing from the spirit of the invention or the scope of the subjoined claims.

I claim:

15 1. A metal sawing machine comprising a hollow base, a feed frame having hollow vertical side members and upper and lower cross members connecting said side members, interfitting guiding ways between the lower cross member and the 20 base to constrain the feed frame to horizontal reciprocatory movement, a fluid pressure motor within the confines of the hollow base and interconnected with the base and the lower cross member for reciprocating the feed frame, a saw frame interfitting with guiding ways on the vertical side members and constrained to vertical reciprocatory movement, and fluid pressure motors housed in the hollow vertical side members and interconnecting the side members and the 25 saw frame for reciprocating the saw frame.

2. A metal sawing machine comprising a base, a feed frame interfitting with guiding ways on the base for reciprocatory movement, said feed frame having hollow side members, a saw frame interfitting with guiding ways on the side members for reciprocatory movement relative to the feed frame, a saw blade fixed to the saw frame, fluid pressure motors for reciprocating the saw frame, said motors being housed in the hollow side members and including cylinders fixed to the side members and pistons operatively connected to the saw frame.

3. A metal sawing machine comprising a stationary frame, a feed frame fitted to guiding ways on the stationary frame, said feed frame comprising cross members and hollow side members connected to the cross members, guiding rails fixed to the side members of the feed frame and having confronting V-shaped guide grooves, a saw frame including cross members and side members connecting said cross members, the side members of the saw frame being formed with V-shaped slides interfitting with the V-shaped guide grooves of the guide rails, the hollow members of the feed frame and the guide rails having registering slots, a pair of fluid pressure motors for reciprocating the saw frame, said motors being disposed in the hollow members of the feed frame and having cylinders fixed to said hollow side members of the feed frame, pistons fitted in the cylinders and having piston rods projecting exteriorly thereof, and driving arms secured to the slides of the saw frame extending through said slots and fixed to the ends of the piston rods.

4. A metal sawing machine comprising a hollow base, a pair of parallel undercut and longitudinally extending guiding rails fixed to the top of the base, a feed frame of rectangular construction and including hollow vertical side members and hollow upper and lower cross members connected to the side members, the lower cross member having guide grooves on its underside slidably interfitting with the guiding rails on the base, a 70 saw frame supported on the vertical members of

the feed frame for vertical reciprocation, and means for reciprocating the feed frame and comprising a fluid pressure motor contained in the hollow base and including a cylinder fixed to the lower cross member of the feed frame, a piston in said cylinder, and a piston rod connected to the piston projecting exteriorly of the cylinder and anchored to the base.

5. A metal sawing machine comprising a reciprocating saw frame, a saw blade, means for anchoring one end of the saw blade to the saw frame, a bar-like saw grip secured to the other end of the saw blade and slidably interfitted with the saw frame, a rack on said saw grip, and a worm rotatably mounted on the saw frame and meshed with the rack whereby when the worm is turned in one direction the saw blade is placed under tension.

10. 6. A metal sawing machine comprising a reciprocating saw frame, a saw blade, means for anchoring one end of the saw blade to the saw frame, a bar-like saw grip secured to the other end of the saw blade and slidably interfitted with the saw frame, a rack on said saw grip, a worm rotatably mounted on the saw frame and meshed with the rack whereby when the worm is turned in one direction the saw blade is placed under tension, a tool engaging stud, and a slip clutch interconnecting the stud and worm to provide for rotative adjustment of the worm while preventing the placing of an excessive tension on the saw blade.

15. 7. In a metal sawing machine the combination of a reciprocating saw frame and a saw blade, of a backing plate engageable with the saw blade, said backing plate having thickened ends formed with elongated slots, an anchor for one end of the plate including a bar-like member fastened to the saw frame and having an undercut hook fixed thereto and engaged in the slot of the adjacent end of the backing plate, an adjustable anchor for the other end of the backing plate comprising a bar provided with a hook engaged in the slot in the adjacent end of the backing plate, said slots being longer than the hooks to permit the backing plate to move toward and away from the saw blade, a rack on the adjustable anchor, a worm rotatably mounted on the saw frame and meshing with the rack, and means for shifting the backing plate toward and away from the saw blade.

20. 8. In a metal sawing machine, the combination with a reciprocating saw frame and a saw blade, of a backing plate engageable with the saw blade, means for anchoring one end of the backing plate to the saw frame, a rack connected to the other end of the backing plate and slidably interfitted with the saw frame, and a worm rotatably supported on the saw frame and meshed with the rack whereby upon rotation of the rack in one direction the backing plate will be placed under tension and held taut in the saw frame.

25. 9. In a metal sawing machine, the combination with a reciprocating saw frame and a saw blade, of a backing plate engageable with the saw blade, means for anchoring one end of the backing plate to the saw frame, a rack connected to the other end of the backing plate and slidably interfitted with the saw frame, a worm rotatably supported on the saw frame and meshed with the rack whereby upon rotation of the rack in one direction the backing plate will be placed under tension and held taut in the saw frame, a tool engaging stud, and a slip clutch interconnecting the stud and the worm to provide for rotative adjustment

of the worm while preventing the placing of an excessive tension on the backing plate.

10. 5. In a metal sawing machine, the combination with a reciprocating saw frame and a saw blade, of a backing plate engageable with the saw blade, means for stretching the backing plate and holding it taut in the saw frame while constraining it to bodily movement toward and away from the saw blade, a pair of clips fixed to the backing plate, an adjusting block cooperable with each clip, an adjusting shaft for each block, each adjusting shaft having an eccentric pin operatively interfitted with its blocks, and means for rotatively adjusting said shafts and releasably securing them in adjusted position.

15. 11. A metal sawing machine comprising a stationary frame, a feed frame interfitted with guiding ways on the stationary frame for horizontal reciprocatory movement with respect thereto, said feed frame having opposed vertical side members cross connected at their upper and lower ends, a vertical guide rail fixed to the inside of each side member, said guide rails having confronting, vertically extending V-shaped guide grooves, a saw frame having vertical side members cross connected at their upper and lower ends, said side members of the saw frame being provided with V-shaped slides slidably interfitted with the guide grooves of said rails, a saw blade carried by the saw frame, means for reciprocating the feed frame, and means for reciprocating the saw frame.

20. 12. A duplex metal sawing machine comprising a stationary frame, a pair of four-sided feed frames supported on the stationary frame for horizontal movement with respect thereto, a four-sided saw frame supported on each of said frames for vertical motion relative thereto, said saw frames having portions offset outwardly from the cutting plane and having portions lying closely adjacent the cutting plane, saws fixed to the portions of the saw frames lying closely adjacent the cutting plane, said saws operating in a common cutting plane and being oppositely disposed with their saw teeth confronting, means for reciprocating the feed frames and means for reciprocating the saw frames.

25. 13. A metal sawing machine comprising a stationary frame, a pair of four-sided feed frames interfitted with guiding ways on the stationary frame for horizontal movement with respect thereto, a four-sided saw frame interfitted with guiding ways on each of said feed frames for vertical movement with respect thereto, said saw frames having portions offset outwardly from the cutting plane and having portions lying closely adjacent the cutting plane, confronting saws fixed to the portions of the saw frames lying closely adjacent the cutting plane and operating in said cutting plane, means for reciprocating the feed frames, means for reciprocating the saw frames, and control devices operated in synchronism with the motion of the saw frames for causing the saw frames to simultaneously partake first of sawing strokes and then of return strokes and for causing the feed frames to feed the saws into the work on each sawing stroke and then retract them a limited distance on each return stroke.

30. 14. A metal sawing machine comprising a stationary frame, a pair of feed frames interfitted with guide ways on the stationary frame for horizontal reciprocatory motion with respect thereto, a saw frame interfitted with guiding ways on each of said feed frames for vertical reciprocatory motion with respect thereto, a

fluid pressure motor for reciprocating each of said feed frames, a fluid pressure motor for reciprocating each of said saw frames, a hydraulic circuit for the fluid pressure motors of each associated feed frame and saw frame, distributing valves in said circuit for reversely actuating the motors, means for synchronizing the action of the distributing valve for the feed frame with the motion of the saw frame, a pilot valve synchronized in its action with the motion of the saw frame and controlling the position of the distributing valve for the fluid pressure motor of the saw frame, and an electromagnetically controlled valve acting in one position to bypass the distributing valves and the pilot valve and effect complete return of the feed frames.

16. A metal sawing machine comprising a stationary frame, a feed frame interfitted with guiding ways on the stationary frame for horizontal reciprocating movement, a saw frame interfitted with guiding ways on the feed frame for vertical reciprocatory motion, a saw fixed to the saw frame, a fluid pressure motor for reciprocating the feed frame, a fluid pressure motor for reciprocating the saw frame, a hydraulic circuit for said motors, a distributing valve for each of the motors incorporated in the circuit, a control valve also incorporated in the circuit, electromagnetic means controlling the position of the control valve, means interconnecting the distributing valve of the feed frame with the saw frame to synchronize the action of the feed frame with the motions of the saw frame, and a pilot valve synchronized in its action with the saw frame and controlling the operation of the distributing valve of the saw frame, said control valve acting upon de-energization of said electro-magnetic means to effect complete return of the feed frame.

17. A metal sawing machine comprising a hollow base, a feed frame interfitted with guiding ways on the base for reciprocatory movement, said feed frame having side members and upper and lower cross members, the lower cross member being hollow, a fluid pressure motor housed within the confines of the hollow base and including a cylinder fixed to the feed frame and a piston fixed to the hollow base, said fluid pressure motor being operable to reciprocate the feed frame, a pump housed in the hollow lower cross member of the feed frame and connected to the opposite ends of said cylinder, a motor carried by the feed frame and having driving connection with said pump, a saw frame interfitted with guiding ways on the feed frame for reciprocating movement relative thereto, a saw blade fixed to the saw frame, and means for reciprocating the saw frame.

18. A metal sawing machine comprising a hollow base, a feed frame having hollow vertical side members and upper and lower cross members, the lower cross member being hollow, interfiting guiding ways between the lower cross member and the base to constrain the feed frame to horizontal reciprocatory movement, a fluid pressure motor within the confines of the hollow base and including a cylinder fixed to the feed frame and a piston fixed to the hollow base, a saw frame interfitted with guiding ways on the side members for reciprocatory movement relative to the feed frame, a saw blade fixed to the saw frame, fluid pressure motors for reciprocating the saw frame, said motors being housed in the hollow side members and including cylinders fixed to the side members and pistons op-

eratively connected to the saw frame, pumps for supplying said fluid pressure motors with fluid under pressure, said pumps being housed in the hollow lower cross member of the feed frame and being carried thereby and being connected to the cylinders of the fluid pressure motors, and an electric motor carried by the feed frame and driving said pumps.

19. In a metal sawing machine, a base having guideways formed thereon, a feed frame guided in the ways on said base for reciprocating movement relative thereto, said feed frame having side members connected at the ends by cross members, the side members of said feed frame having guideways formed thereon, a fluid pressure motor for reciprocating said feed frame, a saw frame having side members connected at the ends by cross members, the side members of said saw frame being formed for reciprocation of said saw frame in the guideways of said feed frame, a fluid pressure motor for reciprocating said saw frame, and pumps connected with the said motors and supplying fluid pressure thereto, said motors and said pumps being mounted on and movable with said feed frame.

20. In a metal sawing machine, a base having guideways thereon, a feed frame mounted on the guideways for horizontal reciprocating movement with respect to the base, the feed frame having guideways thereon, a saw frame fitting in and vertically reciprocable in the guideways on the feed frame, a saw mounted in the saw frame, hydraulically operated motors for severally reciprocating the feed frame on the base and the saw frame on the feed frame, a source of hydraulic pressure mounted on the feed frame and carried thereby, and valves in the connections between the motors and the source of fluid pressure for controlling the flow of pressure to feed the saw into the work on the cutting stroke thereof and then to retract the feed frame for withdrawing the saw from the work for a limited distance during its non-cutting stroke.

21. In a metal sawing machine, a base having guideways thereon, a feed frame mounted on the base guideways for horizontal reciprocating movement with respect to the base, the feed frame having guideways thereon, a saw frame fitting in and vertically reciprocable in the feed frame guideways, a saw mounted in the saw frame, hydraulically operated motors for severally reciprocating the feed frame on the base and the saw frame on the feed frame, a source of hydraulic pressure mounted on and carried by the feed frame, the motors and the source of fluid pressure being connected in a circuit, valves for distributing the flow of fluid pressure in circuit to the several motors, and a valve for controlling supply of fluid pressure to the distributing valves in synchronism with reciprocation of the saw frame to cause movement of the feed frame for feeding the saw into the work on the cutting stroke thereof and then for withdrawing the saw from the work for a limited distance during its non-cutting stroke.

22. In a metal sawing machine, a base having guideways thereon, a feed frame horizontally reciprocable on the base guideways, the feed frame having guideways thereon, a saw frame vertically reciprocable in the guideways on the feed frame, a saw mounted in the saw frame, hydraulically operated motors for severally reciprocating the feed frame on the base and the saw frame on the feed frame, a source of hydraulic pressure

mounted on the feed frame and carried thereby, valves for distributing the flow of fluid pressure from the source to the several motors, a valve actuated by the saw frame to control the supply of fluid pressure to the distributing valves whereby movement of the feed frame feeds the saw into the work on the cutting stroke thereof and then retracts the feed frame whereby the saw is moved away from the work during the non-cutting stroke thereof, and a valve electro-magnetically movable into position to by-pass the distributing valves to cause withdrawal of the feed frame and the saw entirely away from the work.

22. In a metal sawing machine, a base having guideways thereon and having a hollow portion, a feed frame guided on the base ways for reciprocation relative to the base, the feed frame having hollow portions and having guideways formed thereon, a fluid pressure motor mounted in the hollow portion of the base and interconnecting the base and the feed frame for reciprocating

the frame relative to the base, a saw frame guided on the feed frame ways for reciprocation relative to the feed frame, the fluid pressure motors mounted in the feed frame hollow portions and interconnected with the saw frame for reciprocation thereof relative to the feed frame.

23. In a metal sawing machine, a base having a hollow portion and having guideways thereon, a feed frame guided on the ways on the base for reciprocation relative to the base, the feed frame having hollow portions and having guideways formed thereon, a fluid pressure motor comprising a cylinder fixed in the hollow portion of the base and a piston movable in the cylinder and connected with the feed frame for reciprocation thereof relative to the base, a saw frame guided on the feed frame ways for reciprocation relative thereto, and fluid pressure motors mounted in the feed frame hollow portions and connected with the saw frame for reciprocation thereof relative to the feed frame.

ADAM ZISKA.
